CIGARETTE CASE OR SIMILAR ARTICLE

Ara L. White, Edgewood, R. I., assignor of one-third to Thomas A. Glavin, Edgewood, and one-third to William F. Werner, Providence, R. I.

Application December 19, 1951, Serial No. 17,775

Term of patent 14 years

(Cl. D86—9)

To all whom it may concern:

Be it known that I, Ara L. White, a citizen of the United States, residing at 41 Arnold Avenue, Edgewood, Cranston, State of Rhode Island, have invented a new, original, and ornamental Design for a Cigarette Case or Similar Article, of which the following is a specification, reference being had to the accompanying drawing, forming a part hereof.

Figure 1 is a perspective view of a cigarette case or similar article showing my new design.

The back and side not shown in the drawing are identical to the corresponding front and end view shown in the drawing.

I claim:

The ornamental design for a cigarette case or similar article, as shown and described.

ARA L. WHITE.
